JAMES E. WOODRUFF, OF BUFFALO, NEW YORK.

Letters Patent No. 76,026, dated March 24, 1868.

LETTER-BOX.

The Schedule referred to in these Letters Patent and making part of the same.

TO ALL WHOM IT MAY CONCERN:

Be it known that I, JAMES E. WOODRUFF, of Buffalo, in the county of Erie, and in the State of New York, have invented certain new and useful Improvements in Letter-Boxes; and do hereby declare that the following is a full, clear, and exact description thereof, reference being had to the accompanying drawings and to the letters of reference marked thereon, making a part of this specification.

Figure 1 represents a vertical section.

Figure 2 represents a front view, with the lid A thrown up.

My invention relates to that class of letter-boxes that are used upon lamp-posts, and other suitable places in the various parts of a city, for the collection of letters.

The main object of my invention is to construct a letter-box that will prevent the ingress of snow, rain, &c., and at the same time thoroughly secure the packages dropped within from being purloined by persons so disposed.

This box is made of the usual form, and of any suitable metal, having an oblong opening in its top, C, through which the letters are to be dropped. The letter-opening C is protected by a lid, A, which is suitably hinged, and is provided with a small cam, B, at each side, which extends down a short distance into the box. These cams rest upon the forward ends of pivoted levers D, as shown in fig. 1, said levers being metal plates that are secured to each side of the box a slight distance below the top. The rear ends of these levers D are secured to rods E, which extend in an oblique manner toward the centre of the box, where they connect to the lower end of a plate, F, which also extends obliquely from the opposite side of the box. This plate is suitably hinged at its top, and extends from one side of the box to the other, thereby closing one-half of the interior space of the box.

Directly opposite this hinged plate is a stationary plate, G, which is bent at its lower end, as shown, so that whenever the plate F is drawn up to it, it (plate F) will bear against the shoulder thus formed, and effectually close the space and cut off communication to the lower part of the box. The stationary plate may be in the forward part of the box, and the hinged plate may be in the rear portion, thus reversing their present positions.

The box herein represented is provided with a door, I, in its front, which is fastened by a latch, K, and padlock, K', the top being shielded by a bent metal plate, H.

My invention can readily be applied to the letter-boxes now in use.

In the annexed drawings the red lines at z show where the ordinary boxes are hinged; z showing where the front of the lid is connected to the box; y representing a band which attaches the lever, D, to the lid, instead of having it pivoted, so that when the lid is opened by the carrier, the levers, rods, and plate F rise up with it.

It will be seen that by means of the plates F and G there is a V-shaped receptacle formed in the upper portion of the box, and when the lid A is down that a small throat or passage-way is left between these plates for the letters to fall to the bottom of the box. By raising the lid A, its cams B, bearing upon the front ends of the levers D, force the rear ends of said levers upwards, thereby bringing the rods, and with them the swinging plate F, up against the stationary plate G, thus closing the throat and preventing the insertion of a hand or stick, or anything else, into the main portion of the box where the letters are deposited.

The red lines in the drawings show the lid raised and the throat closed. When the lid is again forced down, the passage-way is opened and the letter that has just been dropped into the box will fall to the bottom thereof.

It will be understood that the lid A operates automatically, so that, after the letter is deposited and falls in the V-shaped receptacle, the lid drops and opens the throat to allow the letter to fall to the bottom.

Having thus fully described my invention, what I claim as new, and desire to secure by Letters Patent, is—

The box A, with stationary plate G and hinged plate F, both of which extend obliquely below the lid A,

and form a V-shaped throat, which is opened or closed by the cam B attached to the cover A, lever D, and rod E, substantially in the manner herein set forth.

In testimony that I claim the foregoing, I have hereunto set my hand, this 13th day of January, 1868.

JAS. E. WOODRUFF.
